(57) **CLAIM**

The ornamental design for a display screen or portion thereof with icon for presentation of analyte data, as shown and described.

DESCRIPTION

The file of this patent contains at least one drawing/photograph executed in color. Copies of this patent with color drawings will be provided by the Office upon request and payment of the necessary fee.

FIG. 1 shows a front view of a first embodiment of the display screen or portion thereof with icon for presentation of analyte data;

FIG. 2 shows a front view of a second embodiment of the display screen or portion thereof with icon for presentation of analyte data;

FIG. 3 shows a front view of a third embodiment of the display screen or portion thereof with icon for presentation of analyte data;

FIG. 4 shows a front view of a fourth embodiment of the display screen or portion thereof with icon for presentation of analyte data;

FIG. 5 shows a front view of a fifth embodiment of the display screen or portion thereof with icon for presentation of analyte data;

FIG. 6 shows a front view of a sixth embodiment of the display screen or portion thereof with icon for presentation of analyte data;

FIG. 7 shows a front view of a seventh embodiment of the display screen or portion thereof with icon for presentation of analyte data;

FIG. 8 shows a front view of an eighth embodiment of the display screen or portion thereof with icon for presentation of analyte data; and,

FIG. 9 shows a front view of a ninth embodiment of the display screen or portion thereof with icon for presentation of analyte data.

(Continued)

The broken lines around the icon in the drawings illustrate a display screen or portion thereof and form no part of the claimed design.
